UNITED STATES PATENT OFFICE.

GEORG BUHLMANN, OF BERLIN, GERMANY.

WARP-KNITTING MACHINE.

SPECIFICATION forming part of Letters Patent No. 484,844, dated October 24, 1892.

Application filed May 12, 1892. Serial No. 432,760. (No model.)

To all whom it may concern:

Be it known that I, GEORG BUHLMANN, a subject of the King of Prussia, German Emperor, and a resident of Berlin, in the Kingdom of Prussia, German Empire, have invented certain new and useful Improvements in Warp-Knitting Machines, of which the following is an exact specification.

The object of my invention is to provide such parts on a warp-knitting machine that fabrics resembling plush may be produced by the same; and my invention consists in adding to a warp-knitting machine of usual construction a suitable looper round which the pile-threads are laid. I may also combine with the said looper a knife, serving to sever the pile-threads after the loops have been formed, whereby the nap is produced, giving to the fabric a velvet-like appearance. The loops of the pile-threads may, however, remain as such, and in this case the knife is dispensed with.

In order to make my meaning clear, I have appended hereunto a sheet of drawings, on which—

Figure 1 is a sectional elevation of my improved machine. Fig. 2 is a sectional plan taken on line xx of Fig. 1. Fig. 3 is a front elevation, the warp-thread holder and the upper part of the machine being omitted.

Similar letters denote similar parts throughout the several views.

The construction of the warp-knitting machine is in its main parts the usual one.

35 n are the knitting-needles, moving to and fro. r is the warp-thread holder, moving laterally in a direction perpendicular to the needles n and having, also, an intermittent oscillating motion round the rod p , as indicated on Fig. 40 1. This holder is at its front end provided with holes, through which the warp-threads are passed.

45 h are the pile-thread holders, each being a short sleeve, and g are the weft-thread guides. Both parts h and g are secured to bars which are moved laterally to and fro in the same direction as the warp-thread holder r . The holders h and guides g are removable, so that any required number of the same may be 50 mounted on the said laterally-movable bars,

according to the breadth of the fabric to be produced.

k are the warp-threads.

m are the pile-threads, and w the weft-threads.

s is a stop preventing the warp-threads from moving too high.

v is a rod on which the fabric rests.

As will be seen in Fig. 3, I secure to the frame of the machine a series of vertical bars b , the lower ends of which I prefer to make tapering, and which serve to form the loops of the pile-threads m ; wherefore I have called them "loopers." When it is desired to cut the pile-threads after having formed the loops, I 60 make the looper b tubular at its end and arrange a knife o below the same, the point of said knife entering the looper b . The loopers b and the knives o are secured to the frame of the machine, and are not displaced together 65 with the other parts of the same.

The operation of the machine is the following: The warp-threads and weft-threads are interknit into one another in the usual manner by the reciprocating movement of the 70 needles n and by the lateral displacement of the warp-thread guide r and the weft-thread guides g , so that the needles n pass alternately on different sides of the weft-threads w . At the same time the pile-threads m are 75 moved sidewise, and thus laid around the looper b . At the next movement of the needles n the pile-threads m are completely formed into loops, being drawn backward at the backward movement of the needles by the warp- 80 threads caught in the eyes of the same, and at the same time they are interknit into the ground formed by the warp-threads k and the weft-threads w . The latter may of course 85 also be formed by ornamented strings or bands. In consequence of the tapering form of the looper b the loop of the pile-threads m glides 90 down along said looper, this movement being facilitated by the downward movement of the warp-thread holder r . Thus when the knife o 95 is not employed the loops of the pile-threads will gradually slip off the looper b , and thus a band or course of a looped fabric is produced. When the knife o is placed below the looper b , the loops of the pile-threads m cannot glide off, 100

but are cut by the edge of the knife *o*, whereby the fabric of plush or velvet-like appearance is obtained. The pull of the fabric, which is delivered in the direction indicated on Fig. 1, is sufficient to cause the pile-threads to be severed by the knife *o*.

It is obvious that the knives *o* are removable, so that the warp-knitting machine may be employed, as desired, for the manufacture of one or the other kind of fabrics mentioned above.

Having thus fully described the nature of my invention, what I desire to secure by Letters Patent of the United States is—

15 1. In a warp-knitting machine, the combination, with the needles *n*, warp-guides *r*, and

weft-guides *g*, of the movable pile-thread holders *h* and the stationary loopers *b*, for the purpose as described.

2. In a warp-knitting machine, the combination, with the needles *n*, warp-guides *r*, and weft-guides *g*, of the movable pile-thread holders *h*, the stationary loopers *b*, and stationary knives *o*, for the purpose as described.

In testimony whereof I have signed this 25 specification in the presence of two subscribing witnesses.

GEORG BUHLMANN.
